UNITED STATES PATENT OFFICE.

JULE SEAY BASHAW, OF GAINESVILLE, FLORIDA.

PLACKET-FASTENER.

1,016,909.

Specification of Letters Patent.

Patented Feb. 6, 1912.

Application filed December 31, 1910. Serial No. 600,237.

To all whom it may concern:

Be it known that I, JULE S. BASHAW, a citizen of the United States, and a resident of Gainesville, in the county of Alachua 5 and State of Florida, have invented a new and Improved Placket-Fastener, of which the following is a full, clear, and exact description.

The invention relates to plackets of skirts, 10 and its object is to provide a new and improved placket fastener, arranged to securely hold the placket closed when the skirt is worn and to permit the wearer of the skirt to conveniently close or open the 15 placket.

For the purpose mentioned use is made of two stays pivotally connected with each other at their lower ends and attached to the placket members to overlie one the other 20 when the placket is closed, and a sleeve arranged for removable connection with the upper ends of the placket members, and adapted to engage the free upper ends of the said stays to hold the same against opening. 25

A practical embodiment of the invention is represented in the accompanying drawings forming a part of this specification, in which similar characters of reference indicate corresponding parts in all the views.

Figure 1 is a perspective view of a skirt provided with a placket fastener; Fig. 2 is an enlarged sectional plan view of the upper end of the placket fastener in position 30 on the skirt; Fig. 3 is a side elevation of the pivoted stays; Fig. 4 is an enlarged sectional plan view of the pivotal ends of the stays; and Fig. 5 is a perspective view of the upper ends of the stays, the sleeve detached 40 and parts of the placket members in open position.

The skirt A on which the placket fastener is used is provided with the usual waistband B and with placket members C, C' 45 having pockets for the reception of stays D, D' pivotally connected with each other at their lower ends by a pivot E to allow of the stays D, D' swinging open or closed

thus opening and closing the placket members C, C'. 50

The upper free ends of the stays D, D' are adapted to be engaged by a sleeve F, provided at the opposite sides with buttons F', F² for engagement by buttonholes B', B² formed in the waistband B at the 55 placket members, as plainly indicated in Fig. 5. When the stays D, D' are swung into a closed position the contact members C and C' overlie one the other, and likewise the stays D, D', so that the upper free 60 ends can be readily engaged by the sleeve F which holds the stays D, D' against opening. The buttons F', F² of the sleeve F are engaged with the buttonholes B', B² so that the waistband B is held closed 65 and at the same time the sleeve F is held in position on the upper free ends of the stays D and D'. The stays D and D' are preferably fastened in the pockets of the placket members C, C' by stitches or other 70 fastening means, it being, however, understood that the upper portions of the stays D, D' project beyond the pockets of the placket members C, C', as plainly indicated in Fig. 5, to permit of engaging the sleeve 75 F with the said upper ends of the stays D, D'.

When it is desired to open the placket, the ends of the waistband B are unbuttoned from the buttons F', F² of the sleeve F, 80 and then the latter is removed from the upper ends of the stays D, D' to allow the stays to swing into an open position.

The placket fastener shown and described is very simple in construction and can be 85 readily applied to a skirt to securely hold the placket members in closed position.

Having thus described my invention, I claim as new and desire to secure by Letters Patent:

The combination of placket members provided with pockets and with buttonholes, a pair of stays pivotally connected together at one end and adapted to swing apart, said stays each being disposed in one of said 95 pockets, a sleeve detachably fitted upon the

ends of said stays at the ends thereof opposite the pivotal connection, said sleeve being free of said placket members and provided with a pair of buttons disposed oppositely to each other for the purpose of engaging respectively said buttonholes.

In testimony whereof I have signed my

name to this specification in the presence of two subscribing witnesses.

JULE SEAY BASHAW.
